SIGN

Ramsay G. Regester, Philadelphia, Pa., assignor,
by mesne assignments, to John M. Cole, New
York, N. Y.

Application May 1, 1941, Serial No. 391,259

5 Claims. (Cl. 40—131)

The present invention relates to signs, and is more particularly directed toward interiorly illuminated signs for advertising purposes.

The present invention contemplates signs for these purposes wherein the body of the sign employs flexible, light transmitting plastic sheet material cut to the proper shape or pattern and bent to form to provide an enclosing housing for the light source. This material previous to being bent has been provided with suitable indicia or decoration to provide the sign characteristic desired.

The present invention contemplates signs employing such materials wherein the signs may assume geometric shapes, such as diamonds, triangles, rectangles and the like.

Signs made according to the present invention are very light in weight so as to be easily packed and shipped and there is no likelihood of breakage or damage as in the case of signs employing glass or solid plastics.

Other and further objects will hereinafter appear as the description proceeds.

The accompanying drawing shows, for purposes of illustrating the present invention, two of the many embodiments in which the invention may take form, it being understood that the drawing is illustrative of the invention rather than limiting the same.

In the drawing:

Figure 1 is a front elevational view of a generally triangular shaped sign with parts broken away to show interior construction;

Figures 2, 3 and 4 are top, end and rear elevational views of the sign of Figure 1;

Figure 5 is a view illustrating the flat blank from which the body of the sign of Figures 1 to 4 is made;

Figure 6 is a view illustrating the flat blank suitable for making a diamond shaped sign; and

Figure 7 is a front elevational view of a diamond shaped sign.

Suitable flexible transparent sheet plastic is employed in making the blank such as shown in Figure 5. This plastic is decorated preferably by the silk screen process to give the majority of the sign area a background color and provide decoration, lettering, insignia, trade-marks, pictures, and the like elsewhere on the blank. The blank may then be cut to shape in a die.

As shown in Figure 5 the blank designated generally by the reference character 10 has a central triangular area 11 which is to become the flat front face of the sign. Laterally disposed of the triangular area 11 are two other areas 12,

12 which are to become the cylindrical ends of the sign, and beyond the areas 12, 12 are areas 13, 13 which are to become the back of the sign. The lines intermediate the areas 12, 12 and the central area 11 meet at a point as indicated in Figure 5. From this it will be obvious that the height of the sign body and the slope of the ends are such that the cylindrical ends of the body substantially meet at the top of the flat area 11. Below the area 11 is a tab or flap 14, and to the sides of the areas 13, 13 are similar tabs or flaps 15, 15. The lower edges 16, 16 of the areas 12, 12 are curved. Above the portions 13, 13 are flaps 17, 17 adapted to overlap and the configuration 18 of the upper edge of the blank is such as to provide an opening to give access to a lamp, and permit the bending of one end portion 12 without interfering with the bending of the other end portion. It will be noted that the blank 10 may be cut out of a rectangular piece of material with but little wastage.

The base of the sign is in the form of a board 20. This board has straight front and rear edges 21 and 22, the length of the straight front edge 21 being the same as the length of the flap 14. The ends 23 and 24 of the board 20 are, as here shown, semicircular. These ends may protrude, if desired, and have any shape. This board forms a support for a lamp socket 25 and lamp 26.

The tab 14 is secured to the front edge of the base 20. The material is bent so as to bring the tabs 15, 15 against the rear edge 22 of the base 20 and secured in place with the flaps 17, 17 overlapping. These flaps are secured together by a staple 27. A trimming strip 28 is fastened in place by small brads or nails 29. This trimming strip, preferably made of plastic strip covers the flaps or tabs 14 and 15 and the edges 16 of the blank.

By properly designing the blank the assembled sign will be one in which the front area formed by the triangular portion 12 of the blank will be perpendicular and flat. The end areas formed by the portions 12, 12 will be cylindrical about axes converging toward one another over the center of the sign. The rear wall will also be perpendicular so that from the front the sign is triangular, except for the material removed at the top to provide a hand hole or opening 30 to give access to the lamp.

The sign will be of substantial width and have vertical front and rear walls, as shown in Figure 3. The decoration applied to the front portion 11 may extend on around into the end portions

12, 12, and, when the sign is made up with decoration extending over the areas 11, 12 and 12, the sign presents advertising or other subject matter when viewed from either end or from the front so that observers who are in any position where they can look at the ends or front of the sign are attracted by the indicia on the sign. For example, lettering and a ribbon or other decoration may extend across the areas 12, 11, 12 and pictures of the article being advertised may be on the portions 12 alone.

Where it is desired to have the lamp cord 31 extend in from the rear the blank may be given a suitable configuration to provide an opening indicated at 32. The size and shape of the opening 30 to provide access to the lamp need be only large enough to admit the hand and provide suitable ventilation for the sign.

Figure 6 shows a blank 40 similar to two of the blanks 10 connected at the center and when such a blank is conformed to shape a diamond shaped sign 41 shown in Figure 7 results. This sign provides a different shaped area for the reception of the sign material. The diamond may be mounted with the long side horizontal or vertical, or instead of a diamond shaped sign a square or rectangular shaped sign may be provided. Inasmuch as the form of support of the interior construction of the lamp openings may be varied Figure 7 omits showing such details.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. A sign comprising a sign body formed out of a blank of decorated, flexible, translucent sheet material by bending it into a closed loop with front and rear parallel sides and curved ends, the body having a front flat area converging toward an apex remote from said loop and opposite a perpendicular dropped to the center of the loop, semicylindrical ends having converging axes and continuing from the flat front area around behind the same and meeting the flat rear area, the height of the sign body and the slope of the ends being such that the two semicylindrical ends substantially meet, means for securing the ends of the loop together the ends being disposed midway of the rear flat area the decoration being on the ends and front of the body, a flat base plate having the configuration of the loop and to whose peripheral edges the body is secured, and a lamp socket and lamp secured to the plate.

2. A sign comprising a sign body formed out of a blank of decorated, flexible, translucent sheet material by bending it into a closed loop with front and rear parallel sides and curved ends, the body having a front flat area converging toward an apex remote from said loop and opposite a perpendicular dropped to the center of the loop, semicylindrical ends having converging axes and continuing from the flat front area around behind the same and meeting the flat rear area, means for securing the ends of the loop together the ends being disposed midway of the rear flat area the decoration being on the ends and front of the body, a flat support having the configuration of the loop, the body having tabs extending across the parallel sides of the support and secured to the support, the edges of the body between the tabs being above the support, and a finishing strip about the tabs, the ends of the support and the adjacent edges of the body.

3. A blank for a sign body comprising a sheet of flexible light transmitting material of generally rectangular configuration and bearing sign indicia in a triangular area based on a long side of the rectangle with its sides converging toward the center of the other long side, and additional sign indicia laterally of and adjacent the sides of the triangular area, the blank having tabs along the base of the triangular area and along the remoter portions of the ends, the corners between the tabs being arcuate.

4. An interiorly illuminated sign comprising a flat base of substantial width with parallel front and rear edges, and a sign body made of a sheet of flexible light transmitting material and having a long edge and two short edges at substantially right angles to the long edge when the sheet is flat, the long edge being secured to the front of the base, the shorter edges being secured to the rear of the base, the material being bent about axes converging toward one another from points midway between the front and back edges of the base and opposite the outer ends of the edges secured thereto, and a lamp carried by the base within the body.

5. An advertising sign having a base with parallel sides and substantially semicircular ends, a lamp socket and lamp carried by the base, and a one piece body about the lamp and formed of translucent sheet material, the body having a substantially flat front portion of triangular configuration, end portions of substantially semicylindrical configuration with converging axes which intersects below the top of the body, and a back interconnecting the rear of the end portions, the front of the body being provided with light transmitting indicia.

RAMSAY G. REGESTER.
